(57) **CLAIM**

The ornamental design for a stable bank system, as shown and described.

DESCRIPTION

FIG. 1 is a perspective of one embodiment of a stable bank system of this invention, the system being shown installed in a stable (depicted in phantom lines) forming no part of this invention;

FIG. 2 is a top plan view of the stable bank system;

FIG. 3 is a front view of the stable bank system;

FIG. 4 is a rear view of the stable bank system;

FIG. 5 is a left side elevation of the stable bank system;

FIG. 6 is a right side elevation of the stable bank system;

FIG. 7 is a vertical sectional view taken along lines 7—7 of FIG. 2;

FIG. 8 is a vertical sectional view taken on lines 8—8 of FIG. 2;

FIG. 9 is a perspective of a side panel removed from the stable bank system for clarity of disclosure;

FIG. 10 is a top view thereof;

FIG. 11 is a bottom view thereof;

FIG. 12 is a front view thereof;

FIG. 13 is a rear view thereof;

FIG. 14 is a right side elevation view thereof, the left side elevation being identical;

FIG. 15 is a perspective of a joinder removed from the stable bank system for clarity of disclosure;

FIG. 16 is a top view thereof;

FIG. 17 is a bottom view thereof;

FIG. 18 is a front view thereof;

FIG. 19 is a rear view thereof;

FIG. 20 is a right side elevation view thereof, the left side elevation being identical;

FIG. 21 is a perspective of an end cap removed from the stable bank system for clarity of disclosure;

FIG. 22 is a top view thereof;

FIG. 23 is a bottom view thereof;

FIG. 24 is a front view thereof;

FIG. 25 is a rear view thereof;

FIG. 26 is a right side elevation view thereof, the left side elevation being identical;

FIG. 27 is a perspective of an interior corner member removed from the stable bank system for clarity of disclosure;

FIG. 28 is a top view thereof;

FIG. 29 is a bottom view thereof;

FIG. 30 is a front view thereof;

FIG. 31 is a rear view thereof; and,

FIG. 32 is a right side elevation view thereof, the left side elevation being identical.

The broken line showing of the stable illustrates environmental structure and forms no part of the claimed design.
